UNITED STATES PATENT OFFICE.

ELLA M. HITCHCOCK AND EDD C. HOLLER, OF LOS ANGELES, CALIFORNIA.

SKIRT-MARKER.

1,229,958.

Specification of Letters Patent. Patented June 12, 1917.

Application filed June 5, 1913. Serial No. 771,791.

To all whom it may concern:

Be it known that we, ELLA M. HITCHCOCK and EDD C. HOLLER, citizens of the United States, residing at Los Angeles, in the county of Los Angeles and State of California, have invented certain new and useful Improvements in Skirt-Markers, of which the following is a specification.

This invention relates to improvements in garment marking devices and has particular relation to mechanism by which skirts or dresses may be properly marked and evenly gaged as to length.

It is an object of the invention to provide an apparatus, by which a person may be able to mark her own skirt or dress without other help and secure a proper and even length for finishing the same.

It is also an object of the invention to provide an apparatus having a marking support and provided with clamping means for gripping a garment at the proper height for marking the same at a desired point, the said gripping means being under the control of the individual wearing the garment and being also adapted for holding the skirt or garment entirely around the lower edge thereof.

It is also a further object of the invention to provide a garment marking apparatus having an adjustable platform for holding an individual at different heights, and means for gripping and holding a garment so that it may be marked at a point and height relative to the said platform.

In the accompanying drawings forming a part of this specification:

Figure 1 is a side view of the improved garment marking apparatus portions of the same being broken away and shown in sections to better illustrate the structure thereof.

Fig. 2 is a fragmentary detail sectional view taken upon the line 2—2 of Fig. 1.

Fig. 3 is a fragmentary detail section view through the garment holding means and the adjacent portion of the platform and showing the upper ends of the standards of the machine, the parts being shown upon an enlarged scale.

Fig. 4 is a fragmentary detail view showing in top plan a portion of the marking ring of the device and the clamping pieces with elastic connecting means joining them.

Fig. 5 is a top plan view of the garment marking apparatus.

Fig. 6 is a detail sectional view taken upon the line 6—6 of Fig. 1.

The mechanism forming the subject matter of the present invention is constructed to afford a device upon which a person may stand having on a garment, skirt or dress to be marked, and allow the said garment to hang over a marking support, means being provided which is within the control of the individual wearing the garment, for clamping and holding the garment against said marking support, entirely around the apparatus and until the skirt or garment can be marked. In the drawings the preferred structure of the apparatus has been illustrated and the details and the features of the invention will be described, reference being had thereto.

In the said drawings 10 indicates a base frame, 11 uprights or standards rising from said base and 12 an adjustable platform carried by said standards. The standards 11 are braced at an intermediate point by a transverse frame 13 which connects the said standards, at a point, however, below the platform 12. The upper ends of said standards carry a marking bar or ring 14 against which the garment is to be clamped and marked.

The platform 12 is usually circular in contour and is provided with outwardly extending pairs of jaws 15 adapted to embrace and slide upon the standards 11. The said jaws have edge retaining flanges 16 bearing upon the outer surfaces of the standards 11 to prevent the standards from spreading under weight placed upon the platform.

The standards 11 are provided upon their inner faces with ratchet teeth 17 forming racks upon said standards which are adapted to be engaged by pivoted dogs 18 mounted upon the under side of the platform. The said dogs 18 have inwardly projecting ends 19 which are engaged by springs 20 mounted in sockets 21 upon the under surface of said platform. The outer supporting portions or noses of the said dogs 18 may be drawn inwardly, and out of their normal rack engaging positions, when the platform is to be lowered, by means of flexible connections as chains 22 which extend from the said dogs to a rotating plate 23 which is pivoted upon the under side of said platform 12. An arm or lever 24 projects from said plate 23 to the periphery of the platform 12 and carries an upturned

end portion outside the edge of the platform forming a handle 25. The chains are connected at diametrically opposite points on the plate 23 as clearly shown in Figs 1 and 5 in the drawings so that by turning the said plate through the agency of the handle 25 and the arm 24, the dogs 18 may be withdrawn simultaneously from engagement with the teeth 17 of the standard racks, and 10 against the action of the springs 20, when the platform 12 is to be raised or lowered.

The standards 11 are provided upon their edge faces with scale markings or graduations, the numbers of which indicate different heights from the edge of the garment and the mark thereon to the floor line. The surface of the platform represents the floor line in this respect and the position of said platform with respect to the mark placed 15 upon the garment indicates the height of said garment from the floor when worn by the owner. The mark made upon the garment may even be made below or coinciding with the surface of the platform 12 when the 20 dress or skirt is to touch or drag upon the ground and when the floor is carried down the standards, the height of the garment or dress will increase correspondingly. The standards can be made long enough and 25 graduated to mark clothing for children and young persons as well as for grown people.

An important feature of the invention is the clamping and holding of the garment at the point to be marked, entirely around the 30 lower edge of said garment. In order to properly accomplish this result a series of segmental clamps 26 are provided, and made to have a curvature like that of the marking bar or ring 14. The inner faces of said 35 clamps 26 are usually provided with felt 27 or other yielding holding means. The ends of the clamps do not quite come together in the preferable form of the apparatus when they are bearing against the said ring or 40 the garment overhanging the same. In order to bridge the space between the ends of said clamps and thus prevent the escape of any portion of any garment between them, yielding connecting means 45 is mounted upon and extended from one clamp to another around the machine. Usually the yielding connection is formed by passing an elastic or yielding cord 28 about the said clamps and from the end of 50 one clamp to the adjacent end of the next one as clearly shown in Figs. 1, 4, 5. The said elastic cord is usually passed through inclined apertures at 29 in the ends of the clamps, so as to bring the said cords flush 55 with the inner edges of the clamps where they bridge the spaces between them. It will be readily understood that the elastic cords will yield sufficiently to permit the outward movement of the clamps so as to afford 60 a sufficient space between them and the 65

marking bar or ring 14, to receive the edge of the skirt or other garment.

The movement of the said clamps is preferably within the control of the person standing upon the platform and wearing the 70 garment to be marked. The said clamps 26 are rigidly attached to the upper ends of bars 30 which are generally arranged outside the standard 11 and are movable in and out with respect to the same. To accomplish such movement the lower ends of the said bars 30 are secured to the outer ends of thrust bars 31, a thrust bar being provided for each of said clamp bars 30. The inner ends of said thrust bars 31 are connected to pitmen 32 which extend therefrom to the outer ends of a cross head or disk 33. The pitmen are so connected with the said cross head 33 that when it is rotated the thrust bars 31 will be reciprocated. The 75 said thrust bars are guided in their reciprocation by bearings in the standards 11, and on the base 10.

The cross head 33 is rigidly secured to the lower end of the shaft 34, the said shaft having bearings at its lower end in the base 10 and at its upper end in the brace frame 13. Secured to said shaft 34 near the upper end thereof is a second cross head 35, the arms of which are pivotally connected with 80 pitmen 36 which extend to and are pivotally secured to the inner ends of thrust rods 37. The said thrust rods extend outwardly through bearings 38 upon the frame 13 and bearings 39 in the standards 11 and their outer ends are fastened to the clamp carrying bars 30.

One of the arms of the cross head 35 is made longer than the others and a link 40 connects the same with a lever 41 arranged 85 outside the frame of the device and pivoted at its lower end upon the base 10 at 49. The lever 41 has a hand hold at its upper end by which it may be moved and is provided with a spring actuated latch 42 adapted to engage a toothed segment or rack 43 also secured to the base of the machine. A handle or lever 44 controls the action of said latch. The engagement of the rack 43 by the latch 42, is such that the said lever 41 cannot be 90 moved outwardly and the clamps 26 be thrown outwardly without releasing the latch 42. The said lever 41 can however, be moved inwardly for setting the clamps without manipulating the said latch 42 by hand. In order to make this movement of the lever 41 possible under the control of a person standing upon the platform 12, a cord 45 is connected with a ring on the upper end of lever 41 and made of sufficient length to 95 extend upwardly within reach of the hand of a person occupying the said platform.

It will be observed that the upper and lower cross heads 35 and 33 rigidly connected by the shaft 34 will operate the thrust 100

bars and rods 31 and 37 so as to communicate inner and outer movements to the clamp carrying bars 30 and yet always maintain them in vertical positions.

5 The operation of the mechanism will be readily understood in connection with the above description. If a person desires a skirt or dress made so that its lower edge will be say, about three inches above the 10 floor all around, the platform 12 is set upon the standard 11 so that its upper surface will come opposite the numeral 3 on the scale as shown for instance, in Fig. 1 in the drawings. The clamps 26 are thrown to 15 their outermost positions by pulling the lever 41 outwardly. The person with the skirt or dress on then steps upon the platform 12 and allows the lower edge thereof to hang outside the ring 14, but inside the clamps 20 26. The said person having taken the cord 45 in hand before mounting the platform then pulls upon the said cord, forcing the clamps inwardly and tightly against the garment gripping it upon the outer surface of 25 the ring 14. The latch 42 will hold the parts in this position. The person may then release the skirt or garment and dropping it step from the platform and taking a piece 30 of chalk or other marking material, pass the same along the upper edges of the clamps 26 as indicated in dotted lines at 46 in Fig. 1. The upper edges of said clamps thus become guides for directing a mark to be made entirely around the skirt or garment, and 35 indicating accurately where the lower edge of the garment should be finished. It will thus be evident that a skirt dress or garment may be marked by a person with accuracy and evenness and without the assistance of 40 another person. The details and features of the mechanism may be altered without departing from the spirit of the invention. The platform 12 is preferably provided with apertures 47 and 48 near the center thereof 45 in which the thumb and fingers may be thrust for grasping the platform when it is to be raised or lowered, the other hand of the operator being at the same time used to operate the handle 25 and release the dog 13. 50 It is found in practice that the clamps employed in this device will grip and hold even the thinnest and most flimsy materials, as well as coarser ones, without the least tendency to drawing or pulling them out 55 of shape or into wrinkles, so that the apparatus is well fitted to mark all kinds of goods or materials, without difficulty.

What is claimed is:

1. A garment marker comprising a support 60 for a person, a continuous integral garment supporting band, segmental clamps outside the band adapted to press upon and grip a garment against said continuous integral band, substantially parallel adjustable arms carrying said clamps, adjusting means

connected with the intermediate parts and the lower parts of said arms for advancing or retracting them in parallel relation.

2. A garment marking device comprising a band for holding the garment in spread form, clamps adapted to grip the garment against said band and direct a marking substance around the same and means within the control of the person wearing the garment for setting said clamps 70 simultaneously when standing erect.

3. A garment marking apparatus comprising an adjustable support, a ring capable of holding the garment in spread form and clamps under the control of the operator 80 when standing erect upon said support for gripping the garment against said ring, the clamps directing the location of the mark upon said garment.

4. A garment marking apparatus comprising a frame having graduated standards and a garment engaging member mounted thereon, a person supporting platform adjustably mounted upon said standards, clamps adapted to force a garment 85 against the said garment engaging member, standards carrying said clamps, parallel operating means for drawing said clamps simultaneously toward the garment engaging member to grip the garment and means for 90 bridging the spaces between the ends of said clamps.

5. A garment marking apparatus comprising a frame having rack standards therein, a platform having adjustable means for 100 engaging the said racks of said standards for supporting the platform at different heights, a garment engaging band carried by said standards, segmental clamps for holding a garment against said band bars 105 carrying said clamps and means for moving said bars in and out radially of the apparatus, for holding or releasing the garment.

6. A garment marker comprising a frame having standards provided with rack teeth, a platform adapted to move upon said standards, spring actuated dogs capable of supporting the platform upon the rack teeth, a dog operating disk, flexible connections between the dogs and the said disk and an 110 arm for turning the said disk whereby the said connections will operate to move the dogs out of engagement with the rack teeth when the platform is to be raised or lowered.

7. A garment marker comprising a frame, an adjustable support mounted therein, a garment engaging band, clamps adapted to bear upon the garment and press it against said band, a yielding cord extending from 125 clamp to clamp and bridging the spaces between their ends uprights carrying said clamps and means for moving said uprights toward or away from the adjustable support for causing the clamps to grip or re- 130

lease the said garment, the clamps forming a guiding means for marking material in passing it around the garment.

8. A garment marking apparatus comprising a frame, a platform therein, a garment engaging band, clamps for pressing a garment against said band, bars carrying said clamps, thrust rods for moving the said bars, oscillating cross heads for moving said

10 thrust rods longitudinally and a lever under the control of the party marking the garment for oscillating the said cross heads.

9. A garment marking apparatus having a garment engaging band, clamps adapted to press a garment against said band and having yielding material upon their gripping edges, reciprocating means carrying the said clamps, oscillating cross heads con-

nected with said reciprocating means for moving the same, a shaft carrying the said cross heads, a lever adapted to turn the said shaft and a cord connected with said lever and adapted to extend to the hand of the person wearing the skirt or garment whereby the said person may accomplish the 25 marking operation without the assistance of another person.

In testimony whereof we have hereunto set our hands, in the presence of two witnesses.

ELLA M. HITCHCOCK.
EDD C. HOLLER.
